UNITED STATES PATENT OFFICE.

FRANZ FERDINAND PELTZER, OF SAARBRUCKEN, GERMANY.

AUXILIARY EXHAUST VALVE FOR UNIFLOW STEAM ENGINES.

Application filed June 9, 1924, Serial No. 718,956, and in Germany June 14, 1923.

It is known in uniflow steam engines, for the purpose of obviating or reducing the compression, to provide an auxiliary exhaust port which is controlled by the pressure in the working cylinder. For this purpose the auxiliary exhaust valve is generally connected to a piston moving in a cylinder in connection with the interior of the working cylinder. This auxiliary exhaust valve is under the action of a spring such that the valve opens as soon as the pressure in the working cylinder falls below a predetermined value, and closes on the return of the working piston, after the piston has passed the auxiliary exhaust port, under the pressure of the initial compression.

This known device is satisfactory under ordinary working conditions, but fails with engines, such as locomotives, which are frequently started and stopped. With these engines it may happen that, at the moment when the steam enters the working cylinder, the auxiliary exhaust valve is still open, so that all the working steam escapes through the valve and the engine consequently cannot start.

The invention obviates this drawback by the arrangement by which the piston of the auxiliary exhaust valve is exposed to the pressure of the working fluid by an auxiliary inlet valve which opens somewhat earlier than the main inlet valve, so that the auxiliary exhaust valve is always closed before the main steam inlet valve opens. Since, however, independent of the previous closing of the auxiliary exhaust valve, the compression pressure of the working cylinder, at least in the normal working, must be utilized in order to close the auxiliary exhaust valve, there is according to the invention, between the space in which the piston of the auxiliary exhaust valve moves and the working cylinder, a restricted passage or a throttling device which, when the auxiliary inlet valve is open, establishes the required difference of pressure relative to that in the working cylinder.

Three different examples of constructions according to the invention are shown in Figs. 1 to 3, 4 and 5 of the accompanying drawings, each of which is a sectional view, the working parts being shown in different positions.

Referring to Figs. 1 to 3, 1 is the working cylinder, 2 the working piston, 3 the main

exhaust port of the working cylinder, 4 is an auxiliary exhaust port communicating with a valve chamber 5, in which the auxiliary exhaust valve 6 is arranged. The valve is U-shaped in longitudinal cross-section and 60 is pressed upwards by a helical spring 7. The lift of the auxiliary exhaust valve is limited by an upper bush 8 which connects with the main inlet channel 9. The space 10 between the exhaust valve 6 and the bush 65 8 is connected with the channel 9 by a small restricted passage 11.

The main inlet of the working fluid to the channel 9 is controlled by the main inlet valve 12 which is under the action of the 70 spring 13 and establishes a direct communication between the working fluid inlet 14 and the channel 9.

With this main inlet valve is connected an auxiliary inlet valve 15 which is loaded by 75 a spring 16 and, when open, allows the working fluid to enter through the hollow shaft 17 of the main inlet valve 12 into an annular chamber 18, whence it flows through an intermediate passage 19 into the chamber 10 of 80 the auxiliary exhaust valve 6.

The main and auxiliary inlet valves are operated by means of a rod 20 which, by means of a pin 21, first opens the auxiliary inlet valve 15 and then by its annular end 85 surface 22 opens the main inlet valve 12. On starting the engine, the auxiliary inlet valve 15 is first opened by means of the rod 20; the working fluid then flows from the inlet 14 through the hollow shaft 17, 90 the chamber 18 and the intermediate passage 19 into the chamber 10 over the auxiliary exhaust valve 6 and closes the valve by pressing it down on its seat 23 against the action of the spring 7 (see Fig. 1, in which auxiliary exhaust valve is just starting to move downward). The main inlet valve 12 then immediately opens, so that the working fluid can under no circumstances escape through the auxiliary exhaust valve 6 (Fig. 2). In 100 the normal working the auxiliary inlet valve 15 is more or less inoperative and the auxiliary exhaust valve 6 is closed in known manner by the compression pressure in the working cylinder 1 or in the channel 9, the 105 pressure being transmitted through the passage 11 to the chamber 10 over the valve 6.

The main valve 12 may be provided with fine openings 24 which connect the channel 9 with the hollow shaft 17, and on the one 110

hand accelerate the equilibrium of pressure between the auxiliary inlet space and the working cylinder, and on the other hand provide an initial flow of the working fluid into the working cylinder.

In Fig 3 there is shown the position of the parts, when both inlet valves are closed. The exhaust ports 3 are opened by the piston, in the cylinder and the space 10 is under 10 atmospheric pressure, so that the spring 7 opens the auxiliary exhaust valve 6.

In some circumstances it is preferable to provide the auxiliary exhaust valve with two pistons, one of which is essentially influenced by the pressure in the working cylinder, while the other is entirely controlled by the pressure of the working fluid. It is possible in this way to obtain the most favourable construction for both means of operating 15 the auxiliary exhaust valve.

This construction is shown in Fig. 4. The position of the parts in this figure corresponds to that shown in Fig. 2. The auxiliary exhaust valve 25 is provided with two pistons 26 and 27 of which the upper terminates in the main inlet channel 9 and an annular space 28 surrounds the junction of the two pistons, the piston 26 being of larger cross section than the piston 27. In this 20 arrangement as in the preceding, the main inlet valve 12 is operated together with the auxiliary inlet valve 15, by a rod 20. The passage 19 communicates with the channel 9 through a restricted passage 29. The action 25 is the same as in the construction shown in Fig. 1. During the expansion stroke of the engine the working pressure acts on the piston 27 and holds the valve 25 closed. After the piston 2 at the end of its stroke has 30 freed the exhaust port 3, the pressure is released from the working cylinder 1 and also from the piston 27, and the valve 25 opens under the action of its spring 7. In the 35 normal operation of the engine, on the return stroke of the piston 2 the compression pressure acts on the cross section of the piston 27 and in known manner closes the valve 25. The inflowing working fluid entering through the auxiliary inlet valve 15 and the 40 passage 19 over the piston 26 plays no part in the normal operation of the engine, since in this case the valve 25 is closed when the auxiliary inlet opens. If the engine, however, is to be started from a position in 45 which the piston 2 has not yet covered the auxiliary exhaust port 4, as soon as the inlet port is opened, the working fluid, in consequence of the previous opening of the auxiliary inlet 15, enters into the annular space 28 and closes the valve 25 before the working fluid is admitted through the main inlet valve 12 to the cylinder 1. Consequently, the working fluid cannot escape through 50 the auxiliary exhaust valve. The passages 29 and 24 serve, in this construction, as in

the example shown in Fig. 1, for equalizing the pressure in the cylinder 1 and the space 28.

In the example shown in Fig. 5 the pistons of the auxiliary exhaust valve are separate. The piston 32 is connected with the auxiliary exhaust valve 31 and a second piston 33, closed at the top, moves in the same cylinder. Also in this example there is a main inlet valve 12 with an auxiliary inlet valve 15 operated by a rod 20, by which, through the hollow shaft 17, the inlet 14 and the passage 19 is connected with the auxiliary exhaust valve. Since in this case the pistons 32 and 33 have the same diameter, this construction is simpler and cheaper to manufacture.

An opening 34 in the piston 33 connects the interior of the pistons 32 and 33 with the passage 19.

The action of this construction is the same as that shown in Fig. 4, with this difference only, that, if on starting the engine the auxiliary inlet valve 15 opens and the working fluid enters between the pistons 32 and 33, only the lower piston 32 is pressed downwards, while the upper piston 33 remains in its upper dead position or is forced upwards into this position.

In the normal working, the pistons 32 and 33 are not separated, since on the compression stroke they are moved together downwards by the compression pressure acting on the upper piston 33 and later, after the pressure has been equalized, they are moved 100 together upwards by a spring 7.

The invention is not limited to the described and represented examples, but can be carried out in different ways.

I claim:

1. An engine comprising a working cylinder, a piston reciprocating therein, main and auxiliary exhaust ports uncovered by said piston, an inlet port into said cylinder, a chamber, and a passage connecting said chamber with said auxiliary exhaust port, a valve in said chamber, main and auxiliary inlet valves, means for opening said auxiliary inlet valve before said main inlet valve, a restricted passage connecting said inlet port with one side of said auxiliary exhaust valve, and a passage connecting the said side of the auxiliary exhaust valve with the supply of working fluid when said auxiliary inlet port is opened.

2. An engine comprising a working cylinder, a piston reciprocating therein, main and auxiliary exhaust ports uncovered by said piston, an inlet port into said cylinder, a chamber and a passage connecting said chamber with said auxiliary exhaust port, a valve in said chamber, a spring pressing on said valve and adapted to open it, main and auxiliary inlet valves, means for opening said auxiliary inlet valve before said

main inlet valve, a restricted passage connecting said inlet port with one side of said auxiliary exhaust valve, and a passage connecting the said side of the auxiliary exhaust valve with the supply of working fluid when said auxiliary inlet port is opened.

3. An engine comprising a working cylinder, a piston reciprocating therein, main and auxiliary exhaust ports uncovered by said piston, an inlet port into said cylinder, a chamber and a passage connecting said chamber with said auxiliary exhaust port, a U-shaped spring operated valve in said chamber, a bush inserted in said chamber, a shoulder on said bush limiting the stroke of said auxiliary exhaust valve, main and auxiliary inlet valves, means for opening said auxiliary inlet valve before said main inlet valve, a restricted passage connecting said inlet port with one side of said auxiliary exhaust valve, and a passage connecting the said side of the auxiliary exhaust valve with the supply of working fluid when said auxiliary inlet port is opened.

25 4. An engine comprising a working cylinder, a piston reciprocating therein, main and auxiliary exhaust ports uncovered by said piston, an inlet port into said cylinder, a chamber and a passage connecting said chamber with said auxiliary exhaust port, a U-shaped, spring operated valve in said chamber, a bush open at one end to said inlet port and closed at the other end inserted in said chamber, a shoulder on said bush limiting the stroke of said auxiliary exhaust valve, a restricted passage in the closed end of said bush, main and auxiliary inlet valves and means for opening said auxiliary inlet valve before said main inlet valve, and a passage connecting the said side of the auxiliary exhaust valve with the supply of working fluid when said auxiliary inlet port is opened.

45 5. An engine comprising a working cylinder, a piston reciprocating therein, main and auxiliary exhaust ports uncovered by said piston, an inlet port into said cylinder, a chamber and a passage connecting said chamber with said auxiliary exhaust port,

a spring operated valve in said chamber, 50 main and auxiliary inlet valves, means for opening said auxiliary inlet valve before said main inlet valve, said means comprising a tube integral with said main inlet valve, a valve seat for said auxiliary inlet 55 valve in said main inlet valve, a stem attached to said auxiliary inlet valve disposed within said tube and means for first lifting said valve stem and then said tube.

6. An engine comprising a working cylinder, a piston reciprocating therein, main and auxiliary exhaust ports uncovered by said piston, an inlet port into said cylinder, a chamber and a passage connecting said chamber with said auxiliary exhaust port, 60 a spring operated valve in said chamber, main and auxiliary inlet valves, means for opening said auxiliary inlet valve before said main inlet valve, said means comprising a tube integral with said main inlet 65 valve, a valve seat for said auxiliary inlet valve in said main inlet valve, a stem attached to said auxiliary inlet valve disposed within said tube, a rod, a pin on said rod engaging with said valve stem and a flat 70 end on said rod engaging later with the end of said tube.

7. An engine comprising a working cylinder, a piston reciprocating therein, main and auxiliary exhaust ports uncovered by 80 said piston, an inlet port into said cylinder, a chamber and a passage connecting said chamber with said auxiliary exhaust port, a spring operated valve in said chamber, main and auxiliary inlet valves, means for 85 opening said auxiliary inlet valve before said main inlet valve, said means comprising a tube integral with said main inlet valve, a valve seat for said auxiliary inlet 90 valve in said main inlet valve, fine openings in said main inlet valve connecting said inlet port with the interior of said tube, a stem attached to said auxiliary inlet valve disposed within said tube and means for 95 first lifting said valve stem and then said tube.

In testimony whereof I affix my signature.
FRANZ FERDINAND PELTZER.
